UNITED STATES PATENT OFFICE.

WILLIAM G. HALL, OF HONOLULU, TERRITORY OF HAWAII.

JUICE-STRAINING SYSTEM FOR SUGAR-CANE MILLS.

Application filed January 29, 1926. Serial No. 84,657.

The invention relates to a juice straining system for sugar cane mills and has for its object to provide a juice strainer associated with an intermediate conveyer, preferably between the first and second mills, with means for delivering the mixed juice from the several mills to the bagasse on said intermediate conveyer, so that the filtering action of the bagasse upon the juice will supplement the action of the strainer, located in the bottom of the trough of the conveyer, whereby the strained mixed juice will be in proper condition for immediate delivery to the boiling house. A further advantage of the arrangement of the screen or strainer in the location indicated, is that the normal operation of the conveyer mechanism in feeding the bagasse to the succeeding mill will scrape the surface of the screen and prevent the latter clogging up with cushion.

The invention is illustrated in the accompanying drawings, in which:

Fig. 1 is a diagrammatic side elevation of a four unit mill, involving the invention.

Fig. 2 is a diagrammatic plan view of the intermediate conveyer having the juice screen or strainer located in the bottom of the trough thereof.

Referring to the drawings, 1 indicates a typical crusher to which the cane is fed and, after being crushed, is carried by a conveyer 3, enclosed in housing 2, to a shredder 6, which latter delivers the shredded cane by a conveyer 7 to the first mill 10. The juice expressed by the crusher passes into the bottom section 4 of the boot of the conveyer 3 and is then delivered by the spout 5 to the juice pan 11 of the first mill.

Between each of the mills is located the usual intermediate conveyer, separately indicated by the reference numerals 20, 20' and 20², each conveyer being provided with an endless chain-and-slat scraper 21, which serves to move the bagasse over the bottom of the conveyer trough from one mill to the next. The second, third and fourth mills 10', 10² and 10³ are provided with the usual juice pans 11', 11² and 11³, respectively. The pans 11 and 11' of the first and second mills are connected by pipes 12 and 12' with a pump 13, which is provided with a discharge pipe 14 delivering the

mixed juice from said pans to the top of the 55 blanket of bagasse on the intermediate conveyer 20 between the first and second mills. The pan 11² of the third mill is connected by pipe 12² to a pump 13', which has a discharge pipe 14' delivering the juice to a 60 maceration distributor 15 above the intermediate conveyer 20. Pan 11³ is connected by pipe 12³ to the pump 13' whence it is forced through pipe 14² to a maceration distributor 15' above the conveyer 20' between the second and third mills. The usual water maceration supply 25 is provided above the final intermediate conveyor 20². With this particular arrangement for 65 distribution of the juice, it will be noted 70 that the juice from all of the elements of the mill is ultimately discharged onto the bagasse blanket travelling through the intermediate conveyer 20. The bulk of the juice being that expressed by the crusher 1 and, in the first and second mills, is delivered directly to the top of the intermediate conveyer 20 by pump 13, while the juice expressed by the third and fourth mills is 75 ultimately all delivered to the bagasse on 80 intermediate conveyer 20 by pump 13' and distributor 14'.

Mounted in the bottom of the trough of intermediate conveyer 20 is a screen or strainer 22, lying above a hopper-like receptacle 23 secured to the under side of the conveyer trough and having an outlet 24 at its bottom adapted to be connected to the pipe leading directly to the boiling house. 85 By means of this relatively simple arrangement for the distribution and straining of the mixed juice, the danger of inversion, which is one of the objections the elaborate strainer installations heretofore employed, is wholly obviated, and the mixed juices 90 first filtered through the blanket of bagasse on the first intermediate conveyer and then through the strainer in the bottom of said conveyer, is delivered to the boiling house 95 substantially free from bagasse or impurities, and, by reason of the constant travel of the bagasse and the conveyer slats over the screen, the latter is kept free from obstructions, so that the straining operation 100 is continuous and effective.

What I claim is:

1. In a sugar cane mill, an intermediate conveyer comprising a trough and an end-

less chain scraper operating therein, means for delivering the mixed juice on top of the bagasse on said conveyer, a strainer in the bottom of the conveyer engaged by the 5 scraper, and a receptacle for the strained juice below the strainer.

2. In a system of the class described, the combination of a train of mills and their

intermediate conveyers, a strainer located in the bottom of the conveyer between the first 10 and second mills, a receptacle below the strainer, and means for delivering the mixed juice onto the top of the bagasse on the conveyer containing the strainer.

In testimony whereof I affix my signature.

WILLIAM G. HALL.
